(57) CLAIM

(22) Filed: **May 11, 2000**

The ornamental design for a rotatable guide-roller for flexible tubes and wires, as shown and described.

(30) Foreign Application Priority Data

DESCRIPTION

Nov. 11, 1999 (CH) 126.489

FIG. 1 is a side view of a rotatable guide-roller for flexible tubes and wires showing my new design, the guide-roller having circular symmetry about its longitudinal axis, such that any side view would be essentially the same as FIG. 1;

(51) LOC (7) Cl. **08-05**

FIG. 2 is a top view of FIG. 1; and,

(52) U.S. Cl. **D8/356**

FIG. 3 is a bottom view of FIG. 1.
